UNITED STATES PATENT OFFICE.

CARL W. MERTZ, OF REPUBLIC, MICHIGAN.

MICROMETER WATCH-REGULATOR.

SPECIFICATION forming part of Letters Patent No. 229,162, dated June 22, 1880.

Application filed February 26, 1880.

To all whom it may concern:

Be it known that I, CARL W. MERTZ, of Republic, in the county of Marquette and State of Michigan, have invented an Improvement 5 in Micrometer-Regulators, of which the following is a specification.

The nature of my invention relates to certain new and useful improvements in the construction of micrometer-regulators, whereby 10 the most minute adjustment may be made to the watch-movement.

The invention consists in the peculiar construction, arrangement, and combination of the various parts, all as more fully hereinafter 15 set forth.

I am aware that various regulators have been patented wherein a screw or threaded bolt has been employed to act directly or indirectly upon the regulator-arm, and others 20 by means of attachments to the balance-bridge.

It is a well-known fact that in order to regulate a watch so that it will be a correct time-keeper the most minute movement of the regulator-arm which acts upon the balance-spring must be had. Watch makers and repairers 25 are aware that it requires skill and patience to take down, clean, and readjust a watch provided with a micrometer-regulator such as are now in use, from the fact that in so cleaning 30 the parts which regulate the watch in its movements are, in most cases, necessarily displaced, and when such is not the case they are invariably displaced during the process of cleaning.

It is the object of my invention to construct 35 a regulator by means of which the regulator-arm may be most minutely adjusted, and one which it will be almost impossible to disarrange.

In the drawings, Figure 1 is a plan view of 40 the top plate of a watch provided with my improved regulator. Figs. 2, 3, and 4 are enlarged details of construction.

In the accompanying drawings, which form 45 a part of this specification, A represents the top plate of a watch, upon which are mounted

the balance-bridge B and regulator-arm C, of the usual construction.

The plate A is provided with the slots c c', the former, c, receiving the body of the threaded shaft D, and the latter, c', receiving its head or disk F. The plate A is also provided with recesses r r, which form journal-bearings for the end journals of the shaft D, held in place by the arms a of the index-bridge E, which is 55 secured to the plate by means of the screws b. Upon one end of this shaft D is rigidly secured a disk, F, which has notches cut in its edge and outer face, and by means of which the shaft D is operated. Threaded upon this 60 shaft between the arms a of the index-bridge is a nut, G, provided with a slotted head, H, with which engages a pin, I, projecting downward from the under side of the regulator-arm.

In practice, as the shaft D is turned in either 65 direction the nut G is caused to travel along the shaft and move the regulator-arm, so as to increase or diminish the tension of the balance-spring and cause the watch to have a faster or slower movement, as may be required. 70

When it is desired to clean or repair a watch provided with a regulator constructed as herein described every part may be removed without danger of disturbing the nut G from its 75 regulated position upon the shaft; and in building up it is only required to put the pin I in the slot of nut G, and the watch will keep the same time as before, no regulating being 80 required.

What I claim as my invention is—

The plate A, provided with the slots c c' and recesses r, in combination with the index-bridge E, having arms a, holding the shaft-journals in place, threaded shaft D, nut G, provided with slotted head H, and regulator-arm C, having the pin I, substantially as described, and for the purpose set forth. 85

CARL W. MERTZ.
